UNITED STATES PATENT OFFICE.

ELSBERRY GASTON, OF OTTUMWA, IOWA.

WIRE-BENDING MACHINE.

1,171,711.

Specification of Letters Patent.

Patented Feb. 15, 1916.

Application filed June 21, 1915. Serial No. 35,366.

To all whom it may concern:

Be it known that I, ELSBERRY GASTON, a citizen of the United States, residing at Ottumwa, in the county of Wapello and State of Iowa, have invented certain new and useful Improvements in Wire-Bending Machines, of which the following is a specification, reference being had to the accompanying drawings.

- 10 This invention relates to wire bending machines, and has for its primary object to provide a device for easily and quickly bending and shaping lifting hooks on the handles of a wire pan or plate lifter.
- 15 The invention has for a more particular object to provide a machine for operating upon pan or plate lifters of that character which includes two relatively movable handle members wherein means is provided
- 20 for bending the lifting hooks by a single movement of a lever simultaneously upon the extremities of the handle members.

It is another and more specific object of my invention to provide an oscillatable die member adapted to form one of the lifting hooks, and means for adjusting said die member to vary the extent of its movement.

The invention has for an additional object to provide a wire bending machine

30 which is provided with improved means for initially bending a length of wire from which the device is to be formed, and means for holding the work in proper position upon the work support, whereby the lifting hooks may be readily bent in the wire.

With the above and other objects in view, my invention consists in the novel features of construction, combination, and arrangement of parts to be hereinafter more fully

40 described, claimed, and illustrated in the accompanying drawings, in which,

Figure 1 is a perspective view of the complete machine, showing a pan or plate lifter arranged upon the work support;

45 Fig. 2 is an enlarged longitudinal vertical section of the machine; Fig. 3 is a section taken on the line 3—3 of Fig. 2; Fig. 4 is an end elevation showing the manner of inserting a length of wire in the machine to be initially bent; Fig. 5 is a detail transverse section taken on the line 5—5 of Fig. 2; Fig. 6 is a detail perspective view of the oscillating die member; Fig. 7 is a detail perspective view showing the end por-

tions of the handle members of a pan lifter which have been provided with lifting hooks by means of the present invention; Fig. 8 is a detail perspective view of the slideable implement holding member, and Fig. 9 is a perspective view of the complete implement.

Referring in detail to the drawings, 5 designates an upright post or standard which may be suitably mounted and supported at its lower end. To the upper end 65 of this post and on each side thereof, the metal plates 6 are bolted or otherwise secured, said plates projecting above the post. The horizontally disposed work supporting bar 7 is arranged between the upper ends 70 of these plates and is suitably secured to the same. One end of this bar is obliquely inclined downwardly, as at 8, and in the upper face thereof, a plurality of outwardly projecting pins 9, preferably seven 75 in number, are suitably secured. The work supporting bar 7 has its upper face recessed or cut away, as indicated at 7', and a longitudinally extending groove or channel 10 is also formed in this upper face of the 80 work supporting bar and opens at one end upon the face of the inclined end portion 8 of the bar while the other end thereof communicates with the recess 7'. A metal plate 11 is secured to the upper face of the 85 work supporting bar over this groove and has an open-ended longitudinal slot 11' formed therein. This plate serves as a retaining means for a longitudinally slideable bar 40 which is engaged in the groove 10. 90 An upstanding bolt or screw 41 is fixed in said bar and is adapted for movement in the slot 11' of the retaining plate. The upper end of this bolt is provided with a head 42 for a purpose to be later referred to. In 95 the inner end of the bar 40, a stud or pin 43 is fixed, and this pin engaging the inner end of the plate 11 limits the outward sliding movement of the bar 40 and prevents its entire withdrawal from the groove 10. The 100 transversely projecting pins 12 also project from opposite faces of the bar 7. The pins 9 and 12 are provided for the purpose of initially forming certain bends in the wires of which the implement is constructed, and 105 as the present invention does not include such specific means, the same will not be further referred to in detail.

Upon the opposite end of the work supporting bar 7 with respect to the downwardly inclined portion 8 thereof and upon the side faces of said bar, the upstanding plates 13 are secured. Contiguous to the inner edges of these plates, the upper face of the bar 7 is provided with a socket 14. Upon a transversely disposed pin 15, secured at its ends in the plates 13, the oscillatory die member 16 is mounted. This die member, as clearly shown in Fig. 6 of the drawings, is provided with the spaced ears 17 which are loosely engaged upon the pin 15. One end portion 18 of the die member, projecting from one side of the ears, is relatively short and heavy, while the remaining portion of the die member extending upon the opposite side of the ears, indicated by the numeral 19, is comparatively long and of somewhat less thickness than the portion 18 of said die member. This latter portion of the die member extends inwardly and downwardly into the socket 14 in the upper face of the work supporting bar. Above the pin 15, a second transversely disposed pin 20 has its ends fixed in the upstanding plates 13, and upon this latter pin, one end of a lever 21 is loosely engaged. This lever, adjacent to its pivotally mounted end, is formed with an obliquely inclined lug or projection 22 which is adapted to extend downwardly into the socket 14 in the work supporting bar in the manipulation of said lever, as will be hereinafter more fully explained. For the purpose of limiting the oscillatory movement of the die member 16 in one direction, I provide the adjustable screw shown at 23, which is threaded upwardly into the work supporting bar and has its upper end disposed in the socket 14 immediately beneath the inwardly extending end portion 19 of the die member. It will thus be understood that, by simply adjusting this screw, the extent of downward movement of the inner end of the die member may be varied and the upward movement of the opposite end of the die member correspondingly increased or decreased in extent.

In order to prevent a longitudinal shifting movement of the work upon the supporting bar, vertically disposed U-shaped holding rods 24 are employed, the arms of which extend upwardly through openings 25 provided in the bar 7 adjacent each of its ends. The levers 26 are provided with angular heads 27 and these levers are arranged upon opposite sides of the supporting post 5. One end of each of the heads on the respective levers extends inwardly between the opposite edges of the opposed plates 6 and is pivotally mounted upon a pin 27' which connects said plates. The other ends of the lever heads are notched

or bifurcated, as at 28, to receive the intermediate portions of the respective holding rods 24. It will be apparent that, upon an outward movement of the lower ends of the levers, the holding rods are forced upwardly through the openings in the work supporting bar 7 and their upper ends projected above the upper surface of the bar and into engagement with the wire lifter arranged thereon in such manner as to effectually prevent a longitudinal shifting movement of the lifter.

The pan lifting implement includes two relatively movable elements each formed from a single length of wire bent intermediate of its ends to produce longitudinally extending handle portions shown at A, see Fig. 7. These handle portions of one member are preferably twisted by engaging the wire strands forming the handle member 85 with and bending the same over a series of pins, indicated at 29, which are fixed in one of the plates 6. At the central bend in the wire, the opposed portions of the wire are closely engaged for a short distance, 90 and these portions of the wires which constitute the outer ends of the handle members, are adapted more particularly to be operated upon by the present invention and formed into lifting hooks. The wire lifter 95 is arranged upon the supporting bar 7 in the manner indicated in Fig. 1, the engaged outer end portions of the wire of one handle member A projecting outwardly and between the spaced plates 13, as indicated at B, such extremity of the handle extending beneath the pin 15 upon which the oscillatory die member 16 is mounted. The wire at the outer end of the other handle member A projects inwardly between the opposed wire portions of said handle member and is disposed over the socket or recess 14 in the upper surface of the bar 7. The bar 40 is then forced inwardly upon the work support so that the screw or bolt 41 will be disposed between the opposed portions of the wire handle members and the head 42 of said bolt will bear upon the upper handle member, thereby retaining the implement securely in position upon the work support. The lever 21 is then forced downwardly from the position shown in Fig. 1, so that the lug 22 thereof will engage the inwardly projecting portion C of the handle member which is disposed over the socket 14 and force the same downwardly into said socket and into engagement with the inwardly projecting end portion of the die member 16. This die member is thereby oscillated and the inner end forced downwardly, while the outer end of said member is forced upwardly and into engagement with the extended end portion B of the other handle member so that such extended end of the handle is bent or 130

- forced upwardly to produce the hook thereon. This movement of the die member is, of course, limited by contact of the same with the adjustable screw 23. In this manner, 5 it will be seen that the two hooks on the handle members of the device are simultaneously formed in a single movement of the operating lever. By means of my machine, it will, therefore, be appreciated that 10 the completion of the work is greatly facilitated. At the completion of the operation above described, the retaining or holding rods 24 are drawn downwardly by forcing the levers 26 inwardly and the bar 40 is 15 forced outwardly so that the lifter may be readily removed from the supporting bar 7. 20 Each of the wire rods from which the members of the lifter are formed, is approximately 36 inches in length and, in order to initially bend these wires intermediate of their ends to produce parallel portions, I provide a second lever 30 which is fulcrumed at one of its ends upon the pin 31 fixed in the upstanding plates 13. 25 A groove 32 is cut in the end face of the bar 7 which is disposed between these plates, and the end of the lever 30 is reduced and bifurcated or formed with ears, as at 33, through which the pivot pin 31 is loosely 30 engaged.
- 34 designates a gage plate which extends laterally from one side of the post or upright 5 and is adjustably secured to said post by means of the screws 35, the shanks 35 of which extend through the vertical slots 36 provided in the angular inner end of the gage plate. By loosening the screws, it will be readily seen that this plate may be shifted vertically upon the post. In the use 40 of this portion of the machine, one or more wires indicated at W, is inserted downwardly between the end face 30' of the lever 30 at one side of the ears 33 thereon and the pivot pin 31 until the lower end 45 of said wire rests upon the gage plate 34. The lever 30 is then thrown over to the left so that the end face 30' thereof will engage the wire and force or bend the same outwardly and downwardly around the pin 31. 50 When the lever 30 has been disposed in an outwardly projecting horizontal position, the wire will have been bent upon itself and the parallel longitudinally extending portions formed therein.
- 55 From the foregoing description, taken in connection with the accompanying drawings, the construction, manner of operation, and several advantages of my invention will be clearly and fully understood.
- 60 By means of such a machine, the manufacture of implements of the character referred to will be greatly expedited, and the manual labor incident to the bending of the wire of which such implements are 65 formed, considerably reduced. It will be
- seen that, by the adjustment of the set-screw 23 for the movable die member, the angularity of the lifting hooks with respect to the handle members of the implement, may be varied as desired, within certain 70 limits.
- The machine, as a whole, is of comparatively simple construction and is accurate and reliable in the performance of its several functions. 75
- While I have shown and described the preferred construction and arrangement of the several elements employed, it is to be understood that the invention is susceptible of considerable modification therein, and I, therefore, reserve the privilege of resorting to all such legitimate changes as may be fairly embodied within the spirit and scope of the invention as claimed. 80
- Having thus fully described my invention, what I desire to claim and secure by Letters Patent is:—
1. In a wire bending machine, a movable die member, and a lever adapted to engage one wire to be bent to form a hook thereon 90 and also effect a movement of the die member to engage the same with a second wire to be bent and form a hook in the latter wire.
2. In a wire bending machine, a lever 95 adapted to engage and form a hook in a wire member, and means actuated in the operating movement of the lever to engage a second wire member and form a hook therein. 100
3. A machine for forming terminal hooks upon wire implement handles, including relatively movable elements to simultaneously engage the wire handles and form the hooks therein. 105
4. A machine for forming terminal hooks upon wire implement handles, including a lever to directly engage one wire and form a hook therein, and a movable element engaged by said wire in the formation of the 110 hook to operate upon a second wire handle member and simultaneously form a hook therein.
5. A machine for operating upon implements having two handle members formed 115 of wire, said machine including a lever provided with means to engage one of the wire members and form a hook therein, and a movable element engaged by the hook as it is formed in the first wire member whereby 120 said element is moved and engaged with the second wire member to also form a hook therein.
6. A machine for operating upon implements having two handle members formed 125 of wire, said machine including a lever provided with means to engage one of the wire members and form a hook therein, a movable element engaged by the hook as it is formed in the first wire member whereby 130

4
said element is moved and engaged with the second wire member to also form a hook therein, and means for varying the extent of movement of said element whereby the 5 angularity of the hooks may be predetermined.

7. A wire bending machine for operating upon implements having two wire handles, said machine including a lever provided 10 with a lug to engage one of the wire handle members and form a hook therein, and an oscillatory die block adapted to be engaged by the hook as it is formed and thereby moved to engage the second wire member 15 and form a hook therein.

8. A wire bending machine for operating upon implements having two wire handles, said handles having end portions projecting in relatively opposite directions, said 20 machine including a lever having a lug to engage the end portion of one handle member and bend the same into a hook, and an oscillatory die block engaged by said hook as it is formed whereby the die block is oscillated and engaged with the end portion 25 of the other handle member to also bend the same into a hook extending in a reverse direction with respect to the hook on the first-named handle member.

30 9. A wire bending machine for operating upon implements having two wire handles, said handles having end portions projecting in relatively opposite directions, said machine including a lever provided with a lug to engage the end portion of one handle member and bend the same into a hook, and a movable die block actuated simultaneously 35 with the formation of said hook to cause said die block to engage the projecting end of the other handle member and also bend the same into a hook.

40 10. A wire bending machine for operating upon implements having two wire handles, said handles having end portions projecting in relatively opposite directions, said machine including a lever provided with a lug to engage the end portion of one handle member and bend the same into a hook, a movable die block actuated simultaneously 45 with the formation of said hook to cause said die block to engage the projecting end of the other handle member and also bend the same into a hook, and means for limiting the movement of said die block to vary 50 the form of the hook produced upon the latter handle member.

60 11. A wire bending machine for implements having two wire handles, said handles being provided with end portions extending in relatively opposite directions, said machine including a lever provided with means to engage the projecting end portion of one handle member to form the same into a hook, a movable element engaged by the wire as the hook is formed 65

therein and thereby actuated to engage the projecting end of the second handle member and form the same into a hook, and means for regulating the extent of movement of said element whereby the hooks 70 may be bent into a predetermined form.

7. A wire bending machine for operating upon implements having two wire handles, said handles being provided with end portions projecting in relatively opposite directions, said machine including a supporting bar for the implement provided with a socket over which the end portion of one handle member is disposed, a lever fulcrumed at one end upon the supporting 80 bar and provided with a lug to engage said projection on the handle member and form the same into a hook, and an oscillatory die block having one end projecting into said socket to be engaged by the hook as it is formed upon the handle member, whereby the block is oscillated and the opposite end thereof engaged with the end portion of the other handle member to also bend the same into a hook.

90 13. A wire bending machine for operating upon implements having two wire handles, said handles being provided with end portions projecting in relatively opposite directions, said machine including a supporting bar for the implement provided with a socket over which the end portion of one handle member is disposed, a lever fulcrumed at one end upon the supporting bar and provided with a lug to engage said projection on the handle member and form the same into a hook, an oscillatory die block having one end projecting into said socket to be engaged by the hook as it is formed upon the handle member, whereby the block 95 is oscillated and the opposite end thereof engaged with the end portion of the other handle member to also bend the same into a hook, and an adjustable stop device for limiting the oscillatory movement of the die 100 member whereby the hooks are bent into predetermined form.

14. A wire bending machine for operating upon implements having two wire handles, said handles being provided with end portions projecting in relatively opposite directions, said machine including a supporting bar for the implement having a socket over which the end portion of one handle member is disposed, upstanding plates fixed on the body 115 bar adjacent to said socket, a rod fixed in said plates, an oscillatory die member mounted upon said rod, the projecting end portion of the other handle member extending between the rod and said die member, and a lever mounted between said plates and provided with a lug to engage the end portion of the first-named handle member and form the same into a hook, said hook as it is formed engaging one end of the die member 120 125 130

to oscillate the same and cause the other end thereof to bend the projecting end of the second-named handle member into a hook.

15. A machine for forming terminal hooks upon superposed wire handle members, including a pivoted operating lever and means operating upon the respective handle members in a single movement of the lever to simultaneously form a hook in each of said handle members.

16. In a wire bending machine, a work support, means mounted upon one end of said support for operating upon the work, a slide bar mounted upon the other end of the support, and means carried by said slide bar to engage the work and retain the same in position upon the support.

17. In a wire bending machine, a work support, means mounted upon one end of the support to operate upon the work, a slide bar mounted upon the other end of the support, and an upstanding bolt fixed in said slide bar provided with a head to bear upon the work and securely hold the same in position upon the support.

18. In a wire bending machine, a work support, means mounted upon one end of said support to operate upon the work, said support being provided in its other end with a longitudinal groove, a bar slidable in said groove, a plate fixed to the support over said groove and having an open-ended longitudinal slot, an upstanding bolt fixed in the bar movable in said slot, said bolt having a head to bear upon the work and retain the same in position upon the support, and a stop pin fixed in the inner end of said bar to engage said plate and prevent the complete withdrawal of the bar from said groove.

19. A machine for forming terminal hooks upon the corresponding ends of superposed wire handle members, including a pivotally mounted lever and means operating upon the respective handle members in a single movement of said lever to simultaneously form terminal hooks in said members, and adjust-

able means coöperating with one of the hook-forming elements to predetermine the angularity of the hooks.

20. A machine for forming terminal hooks upon superposed wire handle members, including a pivotally mounted lever provided with means to engage one of the wire members and form a hook therein, and concurrently actuated means operating upon the other handle member to form a hook therein.

21. A machine for forming terminal hooks upon superposed wire handle members, including a pivotally mounted lever provided with means to engage one of the wire members and form a hook therein, concurrently actuated means operating upon the other handle member to form a hook therein, and adjustable means coöperating with said last-named means to predetermine the angularity of said hooks.

22. A machine for forming terminal hooks upon the corresponding ends of wire handle members, said machine including an element to operate upon one of the handle members and form a hook therein, and means engaged and actuated by said hook as it is formed in the handle member to simultaneously engage the second wire handle member and form a hook therein.

23. A machine for forming terminal hooks upon the corresponding ends of wire handle members, said machine including an element to operate upon one of the handle members and form a hook therein, means engaged and actuated by said hook as it is formed in the handle member to simultaneously engage the second wire handle member and form a hook therein, and adjustable means coöperating with the last-named means to predetermine the angularity of said hooks.

In testimony whereof I hereunto affix my signature in the presence of two witnesses.

ELSBERRY GASTON.
